UNITED STATES PATENT OFFICE.

CLAUS HARMSEN, OF GARWIN, IOWA.

PIG-HOLDER.

SPECIFICATION forming part of Letters Patent No. 582,914, dated May 18, 1897.

Application filed January 19, 1897. Serial No. 619,792. (No model.)

To all whom it may concern:

Be it known that I, CLAUS HARMSEN, a citizen of the United States, residing at Garwin, in the county of Tama and State of Iowa, have 5 invented certain new and useful Improvements in Pig-Holders; and I do hereby declare the following to be a full, clear, and exact description of the invention, such as will enable others skilled in the art to which it appertains 10 to make and use the same.

This invention relates to a pig or hog holder; and the object of the invention is to provide a machine for holding animals, especially pigs or hogs, while being castrated.

15 A further object of the invention is to provide a machine for holding animals of the above-mentioned character constructed with a sliding clamp operated by a foot-lever to grasp an animal and adapted to be automatically returned to normal position by releasing said foot-lever.

A still further object of the invention is to provide means for holding the feet of an animal independent of the body-holder.

25 The invention consists in the novel construction and arrangement of parts, as will hereinafter be more fully disclosed in the specification and claims to follow.

In the accompanying drawings, forming 30 part of this application, Figure 1 is a top plan view of the machine in normal position. Fig. 2 is an end view of Fig. 1, showing in dotted lines the sliding clamp moved in clamping position. Fig. 3 is a side elevation of Fig. 1. 35 Fig. 4 is a perspective view of the sliding clamp. Fig. 5 is a top plan view of a modification.

The same letters of reference denote the same parts throughout the several figures of 40 the drawings.

The side frame-piece A is attached to the end pieces B, and the latter are secured to a bench C or other suitable stand or support having uprights D, to which are secured one 45 of the clamping members E.

The bottom F, upon which an animal is placed, extends from one of the end pieces B to the other contiguous with the rigid clamping member E, the inner side of said ends 50 being provided with grooves a.

The sliding clamping member G is of the same shape as the rigid or fixed member and

has lower corner-shoulders b, which engage the top and inner sides of the ends B. Lugs c upon the outside of the member G have a 55 right-angle tongue or projection d, which is opened in the grooves a, and the same lugs form a stop for the outward movement of the sliding clamping member G.

Upon the inner side, at each end of the 60 clamping members E and G, is formed a neck lug h, having a curved edge to engage and substantially fit the neck of the animal.

To the side frame A is pivoted a depending arm H, to which is pivoted at e a foot-lever I. A toothed rack L depends from the bench or stand C for the purpose of holding the foot-lever down as desired. A rope or cord f has one end secured to the foot-lever and the other end is run over a pulley g, set 70 in the side A, and is provided with a weight A' sufficient to overcome the weight of said lever and the sliding clamping member, to which latter member the cord is secured. The sliding member is moved against the 75 fixed member by pressing down the foot-lever, which pulls the rope f, and the latter being secured to the sliding member carries the same up to the fixed member.

The independent means for holding the 80 feet of an animal while clamped in the machine consists of a lever P, pivoted at J, the free end of which engages notches m on one of the uprights D to keep it down, and a rope n, operated through a staple O on the rigid 85 clamping member and having one end secured to the said lever P and the other end formed into a loop p. When the animal is clamped, the hind feet are put into the loop and by pressure on the lever P they are held 90 securely.

It will be observed that the tension on the feet, as well as upon the body of the animal, is at all times under full control of the operator, so that there is no injury done the animal. 95

Referring to the modification shown in Fig. 5, the several parts of the machine are like unto those hereinbefore described, except that the rope M ends where it is secured to the sliding clamping member N, the weight 100 and pulley are dispensed with, and in lieu thereof coil-springs o are employed to return the sliding clamping member to its normal position.

It is obvious that in the manufacture of this machine the clamping members may be curved or bent to more fully conform to the shape of the animal to be operated upon, and 5 the size or shape of the machine may be changed as desired without departing from the spirit of my invention.

Having thus described my invention, what I claim as new, and desire to secure by Letters 10 Patent, is—

- 15 1. In a pig-holder, the combination with the stand having grooved end pieces and connected by a side piece provided with a pulley, of the clamping member fixed to the stand, the depending toothed rack, the slideable member having stop-lugs and tongues integral therewith to engage said grooves, the arm pivoted to the said side piece, the lever pivoted to the free end of the arm, and a rope 20 connected to the slideable member and having one end secured to the foot-lever and the other end passing over the said pulley and provided with a weight, as set forth.
- 25 2. In a pig-holder, the combination of the stand having grooved end pieces, and a side piece having a pulley set into its top edge, of the clamping members extending the whole length of the stand, one of said members being fixed and the other slideable on said ends, stop- 30 lugs on the slideable member having right-angled tongues to engage the said grooves, the arm pivoted to the side piece in vertical line with the said pulley, and having a foot-lever pivoted thereto, and a weighted rope secured 35 to the foot-lever and passing over the pulley, and having the slideable member secured between the pulley and foot-lever, as set forth.

3. In a pig-holder, the combination with the stand having grooved end pieces, a side piece, the pulley in the body of said side piece, 40 the clamping member fixed to the stand, and the depending toothed rack, of the slideable member, stop-lugs on the slideable member, adapted to engage the said side piece, tongues engaging said grooves, the arm pivoted to 45 the said side piece, the foot-lever pivoted to the arm and adapted to be swung with said arm in and out of engagement with the depending rack, and the rope having one end secured to the foot-lever and the other end 50 attached to a weight, said rope passing under the said fixed member and having the slideable member attached, substantially as set forth.

4. In a device for holding the body and feet 55 of animals, the stand having side and end pieces, a toothed rack depending from the stand, a foot-lever pivotally connected to the said side piece to turn vertically and horizontally, the clamping member fixed to the stand, the clamping member slidably connected to the end pieces, the rope connected to the foot-lever and to the slideable member 60 a weight secured to the rope, the notched standard upon the stand, the pivoted hand-lever adapted to engage said notches, and the cord secured to the hand-lever and connected to the fixed clamping member, as set forth.

In testimony whereof I affix my signature in presence of two witnesses.

CLAUS HARMSEN.
